2,230,006

AGITATOR FOR WASHING MACHINES

Jabez Curry Nelson, Syracuse, N. Y., assignor to
Easy Washing Machine Corporation, Syracuse,
N. Y., a corporation of Delaware

Application March 13, 1937, Serial No. 130,785

1 Claim. (Cl. 68—133)

My invention relates to washing machines and, more particularly, to a novel agitator or dolly therefor.

An object of my invention is to provide an agitator, adapted to be mounted in a washing vat for operation therein, capable of washing clothes thoroughly and in a minimum length of time.

A further object of my invention is to provide an agitator for a washing machine adapted to be mounted for operation in a washing tub or vat containing washing fluid and clothes, the agitator being so constructed and arranged as to effect a thorough washing of the clothes in a minimum length of time without causing undue deterioration of the clothes.

My invention further contemplates the provision of a novel agitator for a washing machine which is adapted to cause circulation of the clothes around the vat in one circulatory direction so as to continuously present new clothes surfaces to the washing action of the agitator, whereby during the washing operation the entire body of clothes is subjected to the scrubbing and thread-deforming action of the agitator.

More specifically, my invention contemplates the provision of an agitator having a base, a substantially pyramidal shaped central portion extending upward from the base to or above the normal surface level of cleansing fluid, and a plurality of blades extending outward from the edges of the pyramidal shaped central portion, each of the blades extending substantially in the plane of a face of the central portion.

Other objects and advantages of my invention will be more apparent from the following description when taken in connection with the accompanying drawing, in which:

Figure 1 is a view showing the agitator of my invention and indicating a washing vat in which the agitator is mounted.

Figure 2 is a plan view of the agitator taken on the line 2—2 of Figure 1, in the direction indicated by the arrow.

Figure 3 is a view taken on the line 3—3 of Figure 2, in the direction indicated by the arrow.

Figure 4 is a view showing a modified form of the agitator of my invention.

Figure 5 is a view taken on the line 5—5 of Figure 4.

The agitator of my invention is adapted to be mounted in a vat or tub 11 in which the clothes and washing fluid are placed. The washing vat may be of any desired shape, either square or, as shown in the drawing, circular in cross section.

The agitator, generally indicated by the numeral

12, is preferably mounted centrally of the vat 11 and is driven by a shaft 13 extending upwardly through the bottom of the vat. The drive shaft 13 may be driven by any suitable mechanism and from any suitable source of power, not necessary to be shown or described herein since such driving mechanism for oscillating the agitator is well known in the art to which this invention applies. Preferably, the shaft is driven in an oscillatory manner so as to drive the agitator through an arc of 180°, more or less, at a comparatively high rate of speed somewhere between fifty and sixty oscillations per minute.

The shaft 13 extends upward to or above the normal surface level of cleansing fluid, and the agitator 12 is preferably driven by the shaft in the manner described in the copending application of Peter Eduard Geldhof, Serial No. 55,050, filed December 18, 1935. A sleeve 14, extending concentric with the agitator shaft 13, provides additional support for the agitator, as set forth in said application.

The agitator itself comprises a preferably circular bottom plate or base 16 which may, if desired, be substantially flat or may, as shown in the drawing, be sloped upward or crowned as indicated at 17. Extending upward from the base and rigidly secured thereto is a pyramidal shaped central portion 18 which has faces 19. While I have shown in the drawing a triangular pyramid, it will be appreciated that the pyramid may have any desired number of sides. The faces 19 of the pyramid are preferably flat and meet each other in sharply defined edges 21. Extending outward from each of the edges 21 of the pyramid is a blade 22 which, as shown in Figure 1, is rather wide at the bottom 23 and narrower toward the top 24. Each of the blade edges curves outward and upward from the base and attains its maximum width at the point 26, from which point it slopes inward and upward to merge at the top of the pyramidal shaped central portion with the edge of the pyramid. Each of the blades, as shown more clearly in Figures 2 and 3, is bent slightly out of the plane of the adjacent face of the pyramid. It will be particularly noted that the direction in which each of the blades is bent is the same in the case of each blade. There is thus formed a sharply defined pocket 27 extending the height of the agitator between each blade and the adjacent face of the pyramid. A cap 28 is mounted at the top of the agitator and secured thereto in any suitable manner.

In Figures 4 and 5, I have shown a modification

of the agitator shown and described in Figures 1 to 3, inclusive, wherein the blades 29, instead of being bent forwardly out of the plane of the adjacent face of the pyramid 19, lie in the plane 5 of the face as shown in Figure 5.

When the agitator is placed for operation in a vat containing soap and clothes approximately to the level of the lower edge of the cap 28 and is driven in an oscillatory manner at a speed of 10 oscillation and amplitude as above indicated, the clothes and washing fluid are violently agitated. The clothes are subjected, by the blades 22 of the structure shown in Figures 1 to 3 of the drawing or the blades 29 of Figures 4 and 5 of 15 the drawing, to a thorough thread-deforming action which serves to loosen the dirt particles. Moreover, because the pockets 27 of the structure shown in Figures 1 to 3 of the drawing and the pockets 31 of the structure shown in Figures 20 4 and 5 of the drawing all face in the same direction, the clothes and washing fluid tend to circulate around the vat in one circulatory direction. When the agitator is rotated in a clockwise direction, the clothes are given a violent 25 impetus in the clockwise direction. When the agitator is reversed, the clothes and washing fluid are circulated in the opposite direction, but to a lesser extent, so that the resultant action of the agitator is to cause the clothes and washing 30 fluid to circulate around the vat in a clockwise direction, as viewed in the drawing. The only essential difference in the action of the two agitators of my invention is that that of Figures 1 to 3 of the drawing tends to cause a more decided circulation of the clothes in one direction 35 due to the fact that the pockets 27 are more sharply defined than the pockets 31 of the structure shown in Figures 4 and 5.

While the clothes are circulated in one direction around the vat, there is, at the same time, a definite tendency for the clothes to be drawn

from the side walls of the vat into contact with the agitator. This result is due to the fact that when the agitator rotates in a counterclockwise direction, the suction created in and adjacent the lengthwise pockets formed by the blades 5 tends to draw the clothes from the side walls of the vat toward the pockets.

It will be observed from the foregoing description that the agitators of my invention are of new and novel design and are adapted to cause 10 a definite and positive circulation of the clothes around the vat and an action such as to cause new clothes surfaces continuously to be presented to the scrubbing and thread-deforming action of the agitator. Moreover, it will be apparent that various changes and modifications 15 may be made in the form and relation of parts of the agitator without departing from the spirit of the appended claim.

I claim:

A washing machine comprising a vat, an agitator mounted in said vat and a drive shaft extending upwardly through the bottom of the vat for driving the agitator about a vertical axis in an oscillatory manner, said agitator comprising 25 a substantially horizontally extending base mounted closely adjacent the bottom of the vat, a central substantially pyramidal shaped portion extending upward from the base substantially to the normal surface level of cleansing 30 fluid in the vat, and a plurality of blades extending outward from the edges of the pyramid and rigidly connected thereto, each of said blades extending from one of the edges of the pyramid and being inclined with respect to the vertical, 35 and each of said blades being displaced angularly in the same direction of rotation from each of the planes forming extensions of the two adjacent faces of the pyramid.
